FORMING TOOL

Ray C. Kivley, Oak Park, and George Stuhlfauth, Chicago, Ill., assignors to Western Electric Company, Incorporated, New York, N. Y., a corporation of New York

Application May 15, 1937, Serial No. 142,820

2 Claims. (Cl. 81—15)

This invention relates to forming tools and more particularly to pincers for tightly closing hook eyes.

It is an object of the present invention to provide a simple and inexpensive forming tool.

In accordance with one embodiment of the invention, there is provided a tool for tightly closing a hook eye, comprising a pair of levers movable with respect to each other about a pivot positioned intermediate the ends of the levers for moving a pair of article gripping jaws formed on the ends of the levers toward each other to bend the tip of a partially formed hook eye to a position beyond the body portion of the hook. The pivot, about which the levers are movable, is formed with two eccentrically formed bearing surfaces upon which the levers are mounted and has a lever fixed thereto for rotating the pivot to cause the pivoted levers to move longitudinally with respect to each other for forcing the tip of the hook back into the plane of the body thereof after the bending operation.

A better understanding of the invention may be had by reference to the following detailed description when considered in conjunction with the accompanying drawing, wherein

Fig. 1 is a plan view of a pair of pincers made in accordance with the present invention, wherein the part being formed is shown in dot and dash lines, wherein the levers are broken off to conserve space in the drawing, and wherein the pivot actuating lever is in its right hand position;

Fig. 2 is a side elevational view of the pincers as shown in Fig. 1;

Fig. 3 is a fragmentary plan view showing the position of the jaws after the pivot actuating lever has been moved to its left hand position;

Fig. 4 is a fragmentary side elevational view of the pincers as shown in Fig. 3;

Fig. 5 is an end elevational view of the right end of the pincers with the part to be formed shown in dot and dash lines before the part is bent by the tool;

Fig. 6 is an end elevational view similar to Fig. 5 after the part is bent in the tool by moving the jaws together; and

Fig. 7 is an end elevational view similar to Figs. 5 and 6 with the part shown in dot and dash lines as it will appear after the pivot actuating lever has been moved to its left hand position and released.

Referring now to the drawing, wherein like reference numbers indicate the same parts throughout the several views, a pair of levers 10 and 11 are provided with hook engaging jaws 12

and 13 and are pivoted one to another by a pivot member 14. As shown in Fig. 2, the upper lever 10 is formed integrally with the lower jaw 12, and the lower lever 11 is formed integrally with the upper jaw 13. The lever 11 has a portion 15 thereof directly beneath the left end of the lever 10 and has a portion 16 formed integrally therewith which extends outwardly to the side (below in Fig. 1) and upwardly (Fig. 2) for receiving the pivot pin 14. The right hand end (Figs. 1, 2, 3, 10 and 4) of the lever 11 has the hook engaging jaw 13 formed thereon. This jaw extends over the jaw 12 and has formed therein a rounded slot 17 for receiving a partially formed hook, shown in dot and dash lines at 18.

The pivot member 14 comprises two round bearing portions 21 and 22 eccentrically disposed with respect to each other and freely rotatable in apertures 23 and 24 formed in the levers 11 and 10, respectively. A lever 26 is pinned to the portion 21 of the pivot member 14 by a pin 27, and the portion 22 of the pivot member 14 is threaded to receive a machine screw 28, a washer 29 being interposed between the screw 28 and the lever 10.

The lever 11 has an adjustable stop member 30 mounted therein for limiting the amount of movement of the levers 10 and 11 toward each other and has a pair of stop pins 31 and 32 therein for limiting the rocking movement of the lever 26. The rounded slot 17 conforms to the shape of the hook being formed and at its lower end, in Fig. 1, is of a width slightly larger than the thickness of the stock forming the hook, but tapers as shown at 35 to receive the partially formed hook so that it will engage a substantial portion of the body of the hook. Formed in the jaw 12 is a rounded slot 36 which will engage a small portion of the hook 18 adjacent the tip thereof.

This pincers, which is designed primarily for closing the hooks for guy shields at the point where the hook is permanently attached to the shield, may be operated to tightly close the eye of the hook 18 by placing the hook 18 between the jaws 12 and 13, as shown in Fig. 1, and moving the left hand end, Figs. 1, 2, 3, and 4, of the levers 10 and 11 together. This will cause the tip of the hook to be bent beyond the body portion thereof, as shown in Fig. 6, the hook in place between the jaws 12 and 13 being shown in Fig. 5 prior to the bending operation illustrated in Fig. 6. Due to the configuration of the hook 18, the operation of the levers 10 and 11 will temporarily bend the tip of the hook beyond the body portion thereof. However, the resiliency of the material will per-

mit the tip to move back a slight distance from the position shown in Fig. 6, whereupon the levers 10 and 11 still being held in their closed position, which may be regulated by the adjustable stop 5 member 30, the lever 26 may be moved to the left, Figs. 1, 2, 3 and 4, to move the tip of the hook 18 to the left, as shown in Figs. 3 and 4. This last operation bends the tip of the hook beyond the desired position, but the resiliency of the material 10 will cause it to move back into the desired position, as shown in Fig. 7, upon the release of the lever 26.

Although the forming tool described hereinbefore has been described in connection with the forming of hooks for guy wire shields, it will be 15 apparent that the mode of operation of the tool might be modified somewhat without changing any structural features thereof to permit the use of the tool for forming various types of hook eyes 20 and similar articles. Accordingly, the invention is to be limited only by the scope of the appended claims.

What is claimed is:

1. A pincers for closing hook eyes comprising a 25 pair of actuating levers, eccentric means for pivotally interconnecting said levers, said levers

being freely rotatable on said eccentric means, a jaw portion formed on one of said levers for engaging a substantial portion of the body portion of a hook eye to be closed, a jaw portion formed on the other lever for engaging a small portion of the hook eye adjacent its tip, means for actuating said eccentric pivotal connecting means, said levers being operable to move the jaws toward each other and said eccentric pivotal connecting means being operable to move the jaws relative to each other in substantially parallel planes, means for limiting the movement of said jaws toward each other, and means for limiting the amount of the movement of said jaws in substantially parallel planes.

2. A pincers for closing hook eyes comprising hook-engaging jaws each having a plurality of hook-engaging surfaces, a pair of levers for operating said jaws to bend the hook in one plane, an eccentric pivot for connecting said jaws one to another, said levers being freely rotatable on said pivot, and a lever fixed to said pivot for operating it to move the levers and jaws longitudinally of each other to bend the hook in another plane.
